CARRYING CASE FOR A WIG OR SIMILAR ARTICLE

Morris Friedman, Fort Lee, N.J.
(104 E. 25th St., New York, N.Y. 10010)

Filed Jan. 16, 1967, Ser. No. 5,429

Term of patent 14 years

(Cl. D87—5)

FIG. 2.

FIG. 1.

FIG. 3.

FIG. 4.

FIG. 5.

FIG. 1 is a front elevational view of the carrying case for a wig or similar article embodying my new design, the bottom of the case being plain and unornamented;

FIG. 2 is a side elevational view as seen from the left of FIG. 1;

FIG. 3 is a side elevational view thereof as seen from the right of FIG. 1;

FIG. 4 is a rear elevational view thereof; and

FIG. 5 is a top plan view thereof.

I claim:

The ornamental design for a carrying case for a wig or similar article, as shown and described.
